UNITED STATES PATENT OFFICE

156,125

DESIGN FOR A BRIDLE BIT

Pascal M. Kelly, El Paso, Tex.

Application December 1, 1948, Serial No. 149,899

Term of patent 14 years

(Cl. D38—2)

To all whom it may concern:

Be it known that I, Pascal M. Kelly, a citizen of the United States, and a resident of El Paso, in the county of El Paso and State of Texas, have invented a new, original, and ornamental Design for Bridle Bit, of which the following is a specification, reference is had to the accompanying drawing, forming part thereof, in which:

The figure is a perspective view of a bridle bit, showing my new design.

I claim:

The ornamental design for a bridle bit, as shown.

PASCAL M. KELLY.
